UNITED STATES PATENT OFFICE.

LEON E. LA BOMBARD, OF CHELSEA, MASSACHUSETTS, ASSIGNOR TO SPECIALTY AUTOMATIC MACHINE COMPANY, OF CHELSEA, MASSACHUSETTS, A CORPORATION OF MASSACHUSETTS.

STACKER.

1,382,788.

Specification of Letters Patent. Patented June 28, 1921.

Application filed February 6, 1920. Serial No. 356,701.

To all whom it may concern:

Be it known that I, LEON E. LA BOMBARD, a citizen of the United States, and resident of Chelsea, in the county of Suffolk and 5 State of Massachusetts, have invented certain new and useful Improvements in Stackers, of which the following is a specification.

This invention relates to machines or devices for assembling articles in a row and 10 has particular reference to mechanism known as stackers, employed for grouping and holding flat paper or pasteboard boxes issuing from a machine which converts flat blanks into folded boxes. Such a machine is illustrated in Letters Patent No. 1,346,899, 15 granted to me July 20, 1920, and this application is a continuation, in part, of the application which became said Letters Patent, so far as concerns subject matter common to 20 both said applications.

Folding machines of the kind referred to operate very rapidly, producing some sizes of boxes at the rate of sixty thousand and more an hour. As glue is employed to cause 25 overlapping flaps of the blanks to adhere, and as said flaps always have an inherent tendency to spring up or "pop open," it is essential that the folded blanks shall have no opportunity to open until the glue has 30 set. The higher the rate of issue of the folded blanks from a folding machine, the greater is the difficulty of keeping them under such complete and unbroken control as to prevent occasional boxes from springing 35 open and becoming so interengaged or displaced as to seriously interfere with the uninterrupted production of properly folded and secured boxes.

The principal object of my invention is to 40 provide a machine or mechanism which will keep such control of the folded boxes, including pressure thereon for the necessary length of time to permit the glue to set, as to permit the highest rate of speed of production to be maintained, and also to enable comparatively slow-drying glue to be used.

As manual labor is employed to supply the usual feed hopper of a folding machine with blanks, it is impossible to preserve such uniformity of spacing of the blanks being folded as to result in their being deposited in overlapping condition on a slowly moving platform in the form of a row of uniform vertical thickness. Therefore another object 55 of the invention is to provide means for

holding the folded blanks with their glued flaps in contact while they are being transferred from the delivery end of a folding machine to the presser which is to preserve that contact until the glue sets.

With these and other objects in view the invention consists in the construction and combination of parts substantially as hereinafter described and claimed.

Of the accompanying drawings:

Figure 1 is a side elevation of so much of the machine as is necessary to illustrate the invention.

Fig. 2 is a perspective view of the principal elements of the mechanism appearing 70 in Fig. 1.

Fig. 3 is a view similar to a portion of Fig. 2, showing how a change is effected to meet conditions arising when certain kinds of boxes are to be made.

To enable the present invention to be understood it will not be necessary to illustrate or describe any particular type of box folding machine, as the mechanism herein explained is suitable for use in connection 80 with any machine which folds blanks to flat form with overlapping flaps adhesively connected. Portions of the frame of such a machine are illustrated in Fig. 1 wherein the numerals 8 and 9 respectively designate 85 one of the side plates and brackets of the frame at the delivery end of a folding machine. The folded blanks or boxes pass from the folding mechanism (not shown) to the nip of two belts carried by a swinging frame 90 which includes two members 10 pivotally mounted on shaft 11 and counterbalanced as hereinafter described. It is to be understood that there are two members 10, at opposite 95 sides of the machine, one being behind the one appearing in Fig. 1. The two members 10 are connected by bars 12, and said bars practically form parts of the swinging frame. A suitable anti-friction bearing for the frame on pivot shaft 11 is indicated at 13. Projecting from the upper and lower transverse bars 12 and swinging with the frame members 10, are upper and lower longitudinal castings or webs 14.

An upper carrying belt 15 is mounted on 10 pulleys 16, 17, 18. A lower carrier belt 19 is mounted at one end on a pulley 20. The pulleys 18 and 20 are carried by the webs 14. The two belts 15, 19, are driven as hereinafter described.

The flat folded boxes are taken from the folding machine by the belts 15, 19 and are delivered by said belts onto a wide receiving belt 21 which is supported by suitable rolls 5 and is driven slowly so that the boxes *a* are deposited thereon in overlapping positions and are carried under a pressure belt 22 mounted on a pulley 23 carried by a shaft 24 mounted in a yielding frame a portion of 10 which is shown at 25.

Referring more particularly to Figs. 1 and 2, a bar 26 adjustably supported by the upper web 14 supports at its outer end a post 27 which carries the pulley 16 at its lower 15 end and in the upper end of which is secured a transverse pin 28. Adjustably secured to one end of the pin 28 is an arm 29 in which is adjustably secured a vertical rod 30 having at its lower end a stud 31 on which a 20 disk roll 32 is mounted to rotate freely. Adjustably secured to the other end of transverse pin 28 is an arm 33 in which is adjustably secured a vertical rod 34 having at its lower end a stud shaft 35 on which an 25 elongated roll 36 is mounted to rotate freely.

In practice the rapidly delivered folded boxes arrive on the slowly moving belt 21 in such positions that the overlapping flap portions thereof which carry the adhesive 30 are in alinement with the small elongated roll 36. The folded boxes consist of three thicknesses where the wide roll 36 is to bear, and only two thicknesses where the narrow disk roll 32 is to bear. The roll 36 acts to 35 hold the overlapping flap portions of the boxes in contact with each other while passing to the presser belt 22. As the upper flap is usually narrow it has a tendency to spring up before the glue sets. The roll 36 returns 40 any up-sprung flap into contact with the underlying flap and holds it so until the presser belt 22 is reached. The disk roll or wheel 32 bears on the boxes at one side of the overlapping flaps and serves to insure such complete contact of the boxes with the belt 21 45 that they will enter under belt 22 in uniform alinement.

The belt 15 is driven by a pulley 37 on shaft 38, and the belt 19 is driven by a pulley 50 39 on shaft 11 (Fig. 1). The two shafts are geared and driven to actuate the belts in the direction indicated by arrows.

Secured to one of the pivoted frame members 10 is a bracket 40 from which an arm 55 41, carrying an adjustable weight 42 extends far enough to serve to almost counterbalance the weight of the parts carried at the other side of the pivot 11. By means of said weight the pressure of the rolls 32, 36, on 60 the folded boxes may be adjusted to suit the character of the boxes being acted upon.

It is sometimes desirable to limit the lowermost position to which the frame and the pressers carried thereby can swing, especially 65 when yielding pressers such as presently de-

scribed are substituted for the rolls 32, 36. To this end, a stop 43 is removably mounted in a bracket adjustably carried by one of the frame plates 8. When this stop 43 is in place it projects under one end of the lower 70 cross bar 12.

For some classes of work it is desirable that the pressers carried by the swinging frame shall be yielding ones. To this end the machine is constructed to permit the change to 75 be made expeditiously. By comparing Figs. 2 and 3, a preferred means for effecting this change will be readily understood. To effect the change, the pin or cross bar 28 and all parts carried thereby are removed. Then a 80 wide spring 50 is secured to the face of post 27, and a narrow spring 51 carried by an arm 52 of a rod or bar 53 is mounted in the position shown in Fig. 3 by securing said rod 53 in a hole 54 (Fig. 1) formed in the guide 85 block or clamp 55 which is carried by the upper web 14 and in which block the bar 26 is adjustably mounted.

When the character of the work is such as to render it desirable or preferable to employ the spring members 50, 51, instead of the rolls 32, 36, the stop 43 (Fig. 1) will be pushed in far enough to serve to limit the lowermost position of the swinging frame, and the weight 42 will be set near enough the 90 pivot of the swinging frame so that unless the overlapping blanks *a* should present an unduly thick row the frame will not yield, and the springs will then serve to yieldingly bear upon the row and hold all boxes closed 100 while passing to the presser belt 22. For some kinds of boxes however the springs are liable to cause a disarrangement in the row due to the friction between them and the passing boxes. By withdrawing the stop 43, setting the rolls in place of the springs, and setting the weight 42 at a point to more 105 nearly counterbalance the frame, said rolls will bear upon the passing row of boxes without friction and with the same degree of 110 pressure whether the row is thick or thin. The rolls will follow all variations in thickness of the row.

The reason for employing two rolls or two 115 springs side by side and relatively adjustable is that different types of boxes vary so much in the shapes of their edges which first reach the rolls or springs that it is very difficult to set one roll or one spring in such position that it will never cause disarrangement of some boxes in the row.

An important feature of the invention consists in the tapering throat provided by the space which exists between the receiving belt 21, and the portion of belt 15 running from 120 above pulley 20 to the pulley 16. Said portion of the belt 15 travels in a downwardly inclined direction and guides or deflects each box quickly onto the receiving belt, and the rear end of the space referred to is of such 125 130

height or vertical width as to permit the rear end of each box to drop clear of the front edge of the next box to be delivered, so that no two boxes will become interengaged. The 5 space or throat can be varied in length to suit different sizes of boxes by adjusting the bar 26 in the clamp 55 and properly swinging and setting the arm which carries the upper pulley 17 to cause the belt 15 to operate under 10 correct tension. Such adjustment results in locating the pulley 16 and the roll or spring presser at a greater or lesser distance from the delivery end of belt 19. To permit a wide range of adjustment in this respect without 15 having an undue space between the narrow end of the throat and the presser belt 22, it is customary in practice to provide for adjusting the frame 25 in the direction of its length by suitable means not necessary to illustrate. 20 Whether the machine is adjusted to operate as in Fig. 2 or as in Fig. 3, there is a wide presser in position to bear upon those portions of the boxes which are to be held together by the glue so as to bear equally the 25 full width of the box where the longitudinal band of glue usually employed is located, while a narrower presser is in position to bear upon a portion of each box at one side of the edge of the uppermost flap even when 30 boxes of very narrow widths are being operated upon.

Having now described my invention, I claim:

1. Mechanism of the character described 35 having, in combination, a receiving conveyer, a delivering conveyer for depositing articles on said receiving conveyer, an elongated presser for holding the articles on the receiving conveyer, and means for yieldingly bearing on the articles after they are deposited on the receiving conveyer and are approaching the elongated presser.

2. Mechanism of the character described 45 having, in combination, a receiving belt, an elongated presser belt bearing thereon, means for delivering folded boxes on the receiving belt at a point spaced from the presser belt, and means for yieldingly bearing on the boxes during their travel toward 50 the presser belt.

3. Mechanism of the character described 55 having, in combination, a receiving belt, an elongated presser belt bearing thereon, means for delivering folded boxes on the receiving belt at a point spaced from the presser belt, and a plurality of yielding pressers side by side in position to bear on the boxes during their travel toward the presser belt.

60 4. Mechanism of the character described, having, in combination, a receiving belt, an elongated presser belt bearing thereon, means for delivering folded boxes on the receiving belt at a point spaced from the presser belt, a plurality of yielding pressers

side by side in position to bear on the boxes during their travel toward the presser belt, and means for adjusting said pressers relatively to each other.

5. Mechanism of the character described 70 comprising a receiving belt, means for depositing flat folded boxes thereon in overlapping superposed relationship, and means for yieldingly confining the overlapping boxes while they travel on said belt. 75

6. Mechanism of the character described comprising a receiving belt, means for depositing flat folded boxes thereon in overlapping superposed relationship, means for yieldingly confining the overlapping boxes 80 while they travel on said belt, and means for yieldingly bearing on the boxes before they reach said confining means.

7. Mechanism of the character described 85 comprising a receiving belt, means for depositing flat folded boxes thereon in overlapping superposed relationship, means for yieldingly confining the overlapping boxes while they travel on said belt, and a pair of yieldingly supported rolls in position to 90 bear on the boxes before they reach said confining means.

8. Mechanism for assembling articles in a row, comprising a receiving conveyer, a delivering conveyer for depositing articles 95 on the receiving conveyer, a presser connected with said delivering conveyer and means for supporting the delivering conveyer to permit the presser to bear lightly and yieldingly on the receiving conveyer. 100

9. Mechanism for assembling articles in a row, comprising a traveling platform, a conveyer for delivering articles on the platform, means for operating the platform and conveyer at different speeds to cause the articles 105 to overlap each other on the platform, and means for yieldingly bearing on the articles on said platform.

10. Mechanism for assembling articles in a row, comprising a traveling platform, a 110 yieldingly mounted frame, a pair of belts carried by said frame and projecting over said platform, and a presser carried by the frame in position to bear on articles delivered by said belts to the platform. 115

11. Mechanism for assembling articles in a row, comprising a traveling platform, a yieldingly mounted frame, a pair of belts carried by said frame and projecting over said platform, and means for removably 120 connecting interchangeable pressing members with said frame.

12. Mechanism for assembling articles in a row, comprising a traveling platform, a yieldingly mounted frame, a pair of belts 125 carried by said frame and projecting over said platform, means for removably connecting interchangeable pressing members with said frame, and displaceable means for limiting the lowermost position of the frame. 130

13. Mechanism for assembling articles in a row, comprising a traveling platform, means for providing a tapering space above the platform, means for delivering articles 5 in said space, and means for pressing on said articles at the narrower end of said tapering space.

14. Mechanism of the character described comprising a receiving belt, a presser belt 10 operating therewith, and a yielding frame having a pair of coacting belts to deliver articles to the receiving belt.

15. Mechanism of the character described comprising a receiving belt, a presser belt 15 coöperating therewith, a yielding frame

having a pair of coacting belts to deliver articles to the receiving belt, and means for adjustably counterbalancing said yielding frame.

16. Mechanism of the character described 20 comprising a receiving belt, a presser belt coöperating therewith, a yielding frame having a pair of coacting belts to deliver articles to the receiving belt, and means carried by said yielding frame to direct articles 25 under the presser belt.

In testimony whereof I have affixed my signature.

LEON E. LA BOMBARD.
